UNITED STATES PATENT OFFICE.

GEORGE K. SMITH, OF CHICAGO, ILLINOIS, ASSIGNOR TO THE H. C. STAVER IMPLEMENT COMPANY, OF SAME PLACE.

GRINDING-MILL.

SPECIFICATION forming part of Letters Patent No. 324,181, dated August 11, 1885.

Application filed May 16, 1885. (No model.)

To all whom it may concern:

Be it known that I, GEORGE K. SMITH, residing at Chicago, in the county of Cook and State of Illinois, and a citizen of the United States, have invented a new and useful Improvement in Grinding-Mills, of which the following is a full description, reference being had to the accompanying drawings, in which—

Figure 1 is a plan, the hopper being removed. Fig. 2 is a top view of the hopper, and Fig. 3 a bottom view of the same. Fig. 4 is a plan of the metal frame. Fig. 5 is a vertical section at line $x-x$ of Fig. 1, the hopper being shown. Fig. 6 is a side elevation 15 of the parts represented. Fig. 7 is a detail, and is an elevation of the parts shown. Fig. 8 is a bottom view of the lower grinder. Fig. 9 is a plan view of the lever P. Fig. 10 is a vertical section at line $y-y$ of Fig. 1, the hopper being shown. Fig. 11 is a sectional detail taken at line $x-x$ of Fig. 10, some of the parts being removed. Fig. 12 is a side view, and bottom view of the part shown. Fig. 13 is a top view and side view of the part shown. Fig. 14 is a top and side view of the part shown. Fig. 15 is a side view of the master-wheel. Fig. 16 is a side view of the metal frame.

My invention relates to improvements in 3c grinding-mills; and it consists in the novel construction and combination of parts herein-after described and claimed.

In the drawings, A represents the frame, made of wood, on which the metal frame is 35 supported.

B is a metal frame secured to the frame A. This metal frame consists of an outer ring, a, arms b, and a central horizontal part, c, supported by the arms b.

40 d is a circular projection extending upward a short distance from c, which projection is somewhat smaller in diameter than c, so that the outer portion of c forms a shoulder, e. The parts d and e have a small central opening, 45 f, through which the spindle passes. This metal frame, consisting of the parts a b c d, may be cast in one piece.

C is the master-wheel, consisting of a ring, g, having gear-teeth h on the inside, and 50 arms i, carrying a central ring, j, which fits over d and rests on the shoulder e.

D is a disk having a central opening, k.

E E' are two posts extending up from the disk D.

F is the body of a case in which the grinding-rings are placed. The bottom of this case 55 has a hole in it to receive the spindle. The parts D, E, E', and F may all be cast together.

D is secured to d by means of screws or bolts, and it projects over the ring j of the master-wheel, holding the master-wheel securely in place.

l are sockets to receive the inner ends of the sweeps to which the animals are to be attached.

65 G is the spindle, carrying at its upper end one of the grinders, n. The other grinder, o, is, as shown, cast on the under side of the hopper H, which hopper is provided with a flange, p, which is bolted to ears upon the case F, as shown in Figs. 6 and 10.

q is a delivery-spout.

I is a gear-wheel, and J is a bevel gear-wheel.

I and J are cast together and are secured 75 upon the spindle G by means of a feather, so that the spindle can be moved up and down without changing the position of the wheels I J.

r is a spring around the lower end of the 80 spindle G, and resting on a collar thereon.

K K' are two gear-wheels supported on pins on the frame B and engaging with the pinion I.

M M' are two pinions connected with the 85 hubs of the gear-wheels K K', which pinions M M' engage with the teeth h upon the inside of the master-wheel.

N is a bevel-wheel engaging with J, and is secured to a shaft, O, which shaft is supported 90 in bearings s s.

P is a support and lever, one end of which passes through a slot in the post E, and is prevented from escaping therefrom by a pin, u. The other end of this lever passes through a 95 long slot in the post E', and upon the outer end is pivoted a screw-threaded arm, v, which passes loosely through a hole in the bracket w, which is bolted to the post E'.

a' is a hand-wheel on the top of the screw-threaded arm v. A portion of the lever P is spread out or enlarged, as shown in Fig. 9, leaving an opening between the two sides b' b'.

c' is a sleeve having a trunnion on each side,

which trunnions rest in recesses in the upper edges of the parts $b' b'$.

d' is a sleeve resting on the sleeve c' . The upper part of d' is cup-shaped, as shown.

5 e' is a collar, the under side of which is provided with two small pins, f' , which enter corresponding holes in d' . The collar e' is provided with a set-screw, f'' . The spindle passes through the parts $c' d' e'$. It will thus 10 be seen that the weight of the spindle is carried by the lever P through the medium of the trunnions on the sleeve c' which rest in the recesses in the side pieces, $b' b'$, of said lever. The sleeve c' is prevented from any upward 15 sliding movement on the spindle G by means of the sleeve d' and collar e' , the latter being securely held on the spindle by the set-screw f'' , so that any upward movement of the lever P will cause the spindle G to be correspondingly raised. The master-wheel rests upon 20 the shoulder e , and the projection d serves the purpose of a center-pin. The disk D , which is secured to d , extends over the ring j and holds the master-wheel in place.

25 The spindle G has two bearings, one in the parts $c' d'$ of the frame, the other in the bottom of the case F . It has no support at its lower end, as is usual, but it is supported by the lever P and by means of the sleeves c' and d' 30 and collar e' , the latter being held fast on the spindle by a set-screw. The position of these parts $c' d' e'$ on the spindle can be adjusted by loosening the set-screw f'' and then raising or lowering the spindle.

35 The spindle which carries the grinding-disk n can be raised and lowered by means of the hand-wheel a' , screw v , and lever P without throwing the spindle out of line, because the sleeves $c' d'$ will accommodate themselves to 40 the changed position of the lever P . The lever P , sleeves $c' d'$, collar e' , and trunnions and set-screws which carry the weight of the spindle also have a tendency to support the same at a point about midway between its two bearings, and cause it to run more steady than it 45 otherwise would. The spring r acts upon the

spindle, in addition to its weight, to force it down when the lever P is lowered, and also supports the pinion J .

In the drawings the two grinding-disks are 50 shown a greater distance apart than they will be in actual use.

Through the bevel-wheel N and shaft O power can be communicated from the mill to machinery driven through the shaft O . By 55 loosening the collar t on this shaft O the pinion N can be disengaged from J , when desired.

It is not essential that the hopper and the top of the case F should be made together.

What I claim as new, and desire to secure by 60 Letters Patent, is—

1. In a grinding-mill, the combination of the posts $E E'$, carrying the upper grinding-disk and attached to or formed with the disk D , the spindle G , carrying the lower grinding-disk, 65 the master-wheel C , and the frame B , consisting of the ring a , arms b , and horizontal part c , substantially as described.

2. In a grinding-mill, the combination of the main frame B , master-wheel C , disk D , 70 posts $E E'$, case F , spindle G , grinding-disks $n o$, and lever P , adapted to carry the weight of the spindle, substantially as and for the purposes specified.

3. In a grinding-mill, the combination, with 75 the posts $E E'$, carrying the upper grinding-disk, o , and the spindle G , carrying the lower grinding-disk, n , of the divided lever P , pivoted in one of the posts $E E'$, sleeves $c' d'$, and collars e' , substantially as described.

4. A grinding-mill comprising the supports $E E'$, carrying the upper grinding-disk, the disk D , the spindle G , carrying the lower grinding-disk, the frame B , master-wheel C , pinion I , and bevel-wheel J , secured to spindle G , and bevel-wheel N , secured to shaft O and meshing with wheel J , substantially as described. 85
